(57) **CLAIM**

The ornamental design for a combination rebar positioner and fastener, as shown and described.

DESCRIPTION

FIG. 1 is a perspective view of a combination rebar positioner and fastener, showing our new design;

FIG. 2 is a front elevation thereof;

FIG. 3 is a rear elevation thereof;

FIG. 4 is right side elevation view thereof;

FIG. 5 is left side elevation view thereof;

FIG. 6 is a bottom plan view thereof; and,

FIG. 7 is a top plan view thereof.
